UNITED STATES PATENT OFFICE.

CHARLES STEWART, OF WASHINGTON, DISTRICT OF COLUMBIA.

IMPLEMENT FOR CUTTING GRASS.

SPECIFICATION forming part of Letters Patent No. 488,667, dated December 27, 1892.

Application filed June 1, 1892. Serial No. 435,223. (No model.)

To all whom it may concern:

Be it known that I, CHARLES STEWART, a citizen of the United States, residing at Washington city, District of Columbia, have invented a new and useful Implement for Cutting Grass, Grain, Weeds, &c., of which the following is a specification.

In the accompanying drawings Figure 1 is a perspective view of the handle and blade. Fig. 2 is plan view of the blade.

My improvement consists of a curved blade, or cutter, A shown in perspective in the accompanying drawings, attached to the straight handle B, the plane of the blade being at right angles with said handle, which is provided with adjustable, or sliding, rubber grips C, C. These rubber grips are provided for the purpose of giving the hands a better purchase on the handle, and also to obviate the necessity

of a stooping position, such as the handles of the ordinary seythe snath require, and which are at right angles with the snath or handle.

The combination of the rubber grips C, C, with the straight handle B enables the user to maintain an upright or erect attitude, instead of a bending and stooping one as required in the use of an ordinary seythe.

The improvements I claim in a seythe are

The combination of a straight handle provided with rubber grips capable of sliding upon the handle, and a curved blade set in a plane at right angles to the plane of the handle substantially as described in the drawings and specification.

CHARLES STEWART.
